UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed September 17, 1921, Serial No. 501,229. Renewed October 8, 1923.

To all whom it may concern:

Be it known that I, JOHN WALDHEIM, a citizen of the United States, residing in Elizabeth, in the county of Union and State 5 of New Jersey, have invented certain new and useful Improvements in Typewriting Machines, of which the following is a specification.

This invention relates to sound-deadening 10 casings or hoods for typewriting machines of the continuous billing variety, one form of which machine is shown in the patent to Wernery and Smith, No. 1,132,055, granted March 16, 1915. The sound-deadening casing or hood is in the nature of an improvement 15 on the casing disclosed in my prior application, Serial No. 493,786, filed August 20, 1921.

In the Underwood continuous billing machine, the usual letter-feeding carriage has a rearward extension, upon which a carbon-sheet carriage may move forwardly and rearwardly. A web comprising work-plies 20 is fed in from the rear of the machine. The 25 work-plies are interleaved with the carbon-sheets attached to said carbon-carriage, and the work-plies and carbon-sheets are fed forwardly around the platen to the printing point. The work-plies usually comprise a 30 succession of similar printed forms, and, when a form has been typed, the platen is swung upwardly and forwardly in a swing-frame mounted on the carriage, to permit the sheets to be straightened out, so that the 35 carbon-sheets may be more easily retracted or shifted to co-operate with a fresh portion of the web. The typed forms are then gaged against a gage carried by the platen-swing-frame and severed by a knife carried by said 40 frame adjacent the platen.

The present invention provides a hood or casing which deadens the noises arising in the typing operation, while permitting easy access to and operation of the machine. For 45 this purpose, the casing comprises a body-part and a cover part, said body-part being provided with a large front opening to permit insertion of the machine into the casing, and being sufficiently large to receive the 50 entire machine with the exception of the banks of keys which project forwardly from the body-part. A detachable front plate

may be mounted at the front of the body-part to facilitate inserting the machine into the casing.

The body-part and cover-part completely 55 enclose the machine with the exception of the forwardly-projecting banks of type-keys. It is desirable that the usual typing operation be carried on without removing 60 the casing or unnecessarily raising the cover-part. For this purpose, the cover-part comprises a forward portion and a rearward portion, the latter being hinged at its rear end to the body-part, said portions forming 65 a slot at their meeting edges through which the gage-bar of the platen-swing-frame-gage may extend. The carbon-carriage is returned by mechanism mounted on the outside 70 of the casing, and the rearward portion 70 of the cover part, therefore, need not be raised when the carbon-sheets are to be shifted to a new set of forms, but only when access to the carbon-carriage proper is desired, as for the purpose of renewing the 75 carbon-sheets. To permit the platen-swing-frame to be swung forwardly, the forward portion of the cover-part is in the form of a swing-frame which can be swung forwardly out of the path of the platen-swing-frame. 80 To provide access to the front of the typewriter, as for the purpose of making erasures, without necessitating the swinging of the cover-swing-frame, the latter is provided with a door which preferably has a window 85 to permit the typewriting on the platen to be viewed.

To permit the various carriage-operating levers to be operated from outside the casing, the cover-swing-frame terminates a 90 short distance above the front cover-plate to form a slot through which said levers extend. Since the banks of type-keys and the carriage-operating levers are operable from outside the casing, substantially all of the 95 ordinary typing operations can be carried on without removing the casing or raising the cover-part.

Suitable sound-deadening material is provided for closing the slot at the meeting 100 edges of the cover-part portions and the slot through which the carriage-operating levers extend to prevent escape of sound therethrough.

Other features and advantages will hereinafter appear.

In the accompanying drawings,

Figure 1 is a side view, vertically sectioned, of the sound-deadening casing applied to an Underwood continuous billing machine.

Figure 2 is a plan view of the device shown in Figure 1.

Figure 3 is a front view, partly sectioned, of the device shown in Figure 1.

Figure 4 is a view similar to Figure 1, but showing the forward portion of the cover-part in open position and the platen-frame in its sheet-gaging position, and also indicating by dotted lines the open or raised position of the rear portion of the cover-part.

The Underwood continuous billing machine comprises a main frame 10 supported by feet 11 upon a base, not shown, but which may be of sound-deadening material, said main frame having a forward extension 12 in which are positioned banks of type-keys 13 operating type-bars 14 to cause types 15 carried by said type-bars to print against a platen 16 mounted in a platen-frame 17. Said platen-frame forms part of a carriage 20 mounted for letter-feeding movement upon a front rail 21 and a rear rail 22 on the main frame 10. Said carriage is provided with a rearward extension 25 supported at its rear upon a rail 26 on a rearward extension 27 of the main frame 10, the extension 27 being supported at the rear by feet 27*. Said carriage extension 25 is provided with side rails 28 upon which is mounted for forward and rearward movement an auxiliary carbon-carriage 29 having stepped side pieces 30 upon which are positioned bars 31 for fastening carbon-sheets 32 to said carbon-carriage.

A web comprising plies of work-sheet 35 is led over a guide-bar 36 on the rear of the extension 25 between side gages 37 and the plies have interleaved between them the carbon-sheets 32. The work-plies and carbon-sheets are then led forwardly beneath the platen to the printing point. The work-plies 35 usually have printed thereon a series of similar successive forms, each of which is typed and torn off before the next form is in position to be typed. When a form has been fully typed, the platen 16 is swung upwardly and forwardly by means of the swinging frame 17 in which said platen is carried and journaled, said swinging frame being pivotally mounted in the end walls of the carriage 20. The platen being thus swung upwardly and forwardly enables the work-plies and carbon-sheet to be straightened out, so that little resistance is offered when the carbon-sheets are displaced or retracted to co-operate with a fresh portion of the web by pushing rear-

wardly a handle 40 connected to the carbon-carriage 29, the rearward movement of said carbon-carriage being limited by a stop 41. The typed work-plies are then gaged against a gage 42 on a gage-bar 43 carried by the swinging frame 17, and are severed by a front knife 43* carried by said frame after the platen has been returned to its typing position.

To deaden the sounds arising in the typing operation and other devices on the machine, there is provided a sound-deadening casing or hood having a body-part indicated generally at 60, and a cover-part comprising a forward portion indicated at 61 and a rearward portion indicated at 62. The body-part comprises a rear wall 64, side walls 66, and a front wall in the form of two end portions 67, said end portions being spaced apart to permit the insertion of the machine 85 into the casing. The body-part is provided with lateral extensions or pockets 68, to accommodate the travel of the typewriter-carriage and its extension 25 to the right and left. It is further provided with a rearward overhanging extension 69, in which the rear of the carriage-extension 25 operates. When the machine is positioned within the casing, the forward extension 12 extends forwardly from the casing to expose the banks of keys 13. To assist in inserting the machine into the casing and to close all of the front opening not occupied by said forward extension 12 of the machine, there may be provided a front cover-plate 70, detachably secured to end portions 67 by means of turn-buttons 71 having latches 72 fixed thereto, said latches catching behind said end portions to fix the cover-plate in position. The body-part of the casing thus completely encloses the machine, with the exception of the forward extension 12, on all sides except at the top.

To provide a suitable closure at the top of the machine, there is provided the cover-part comprising the forward portion 61 and the rearward portion 62. The latter may be hinged at its rear end to the body-part at 80 and extend forwardly to the gage-bar 43 when said gage-bar and the platen-swing-frame are in their normal positions. The rearward portion 62 of the cover-part thus covers substantially the entire carriage-extension 25, upon which the carbon-carriage reciprocates. To permit the carbon-carriage to be returned to its rearward position before beginning the typing of a new set of forms and without raising portion 62, the return handle 40 is mounted for movement on the upper surface of portion 62 outside of the casing. The handle 40 is reciprocable forwardly and rearwardly on portion 62 and is connected to the carbon-carriage by the engagement of the forked end 84 of a projection 82 with a lateral bar 85 fixed

to the carbon-carriage, the projection 82 being fixed to the handle 40 and operating in a slot 83 in the portion 62. It will thus be seen that the carbon-carriage and the handle 40 may move together forwardly or rearwardly regardless of the position of the typewriter-carriage and the carbon-carriage relative to the machine, since the forked end 84 of projection 82 will always be in sliding engagement with bar 85, while permitting letter-feeding movement of the carriage and said bar. To return the carbon-carriage, it is only necessary to push handle 40 rearwardly. Thus, it is necessary to raise cover-portion 62 only when access to the carbon-carriage is desired, as for the purpose of renewing the carbon-sheets. To guide and support the handle 40 in its movement, it may be mounted on a plate or platform 75, to the under surface of which is fixed the projection 82 and rollers 76, said rollers operating preferably on both sides of guide-bars 77 fixed to the rearward portion 62. The slot 83 may be kept closed by slot-closing cushions 86 and 87 (Figure 3). The rearward movement of the handle 40 may be limited when released from the carbon-carriage by the extension 82 engaging in the rearmost part of the slot 83. The forward portion 61 completes the top closure of the casing and is so mounted that its rearward edge terminates adjacent the forward edge of the rearward portion and just in front of gage-bar 43 when the latter is in its normal position. A slot is thus formed between the two portions, through which the gage-bar 43 extends and in which it may travel sidewise. To close the slot, there may be provided a cushion 87 of sound-deadening material, here shown as mounted adjacent the forward edge of the rearward portion, but it is to be understood that an additional cushion may be mounted, if desired, on the rear edge of the forward portion 61. The forward portion 61 terminates at its forward edge some distance above the top of front plate 70, thus forming a slot through which the various carriage-operating levers, including the line-space lever 88, may extend, so that the carriage may be operated from outside of the casing. The slot may be closed by strips of sound-deadening material 89 and 90 mounted adjacent the edges of the slot.

When a typed form is to be severed, the platen-swing-frame and the attached gage must be swung forwardly. This forward movement, however, would ordinarily be obstructed by the forward portion 61 of the cover-part, and it is, therefore, necessary to swing said cover-portion 61 out of the path of the platen-swing-frame and its gage. For this purpose, said portion 61 is swingably mounted and preferably forms part of a

cover-swing-frame comprising depending ears 91 extending downwardly from the forward portion 61, said ears being pivoted near their lower ends at 92 preferably on brackets 93 fixed to the body-part. By 70 swinging this cover-swing-frame forwardly about pivots 92, which may be done by means of a finger-piece 92^a, the platen-swing-frame and gage 42 may be swung forwardly without obstruction. The cover-portion 61 may be swung into the position shown in Figure 4 with the strip 89 resting on the extension 12, and allowed to rest in this position while the frame 17 is swung forward, the usual operations are performed 75 with the work-plies 35 and the carbon-sheets 32, and the frame 17 is restored to its usual position.

To permit access to the mechanism at the upper front of the typewriting machine 85 without swinging the cover-swing-frame forwardly, the latter may be provided with a door 95 hinged thereto. The forward portion is provided with a transparent plate or window 96 to permit the machine in the interior of the casing to be viewed, said window being set preferably in the door 95.

The rear feet 27^a of the machine may engage in holes 100 formed in forward extensions 101 of the lower part of the rear 95 wall 64 so as to locate the machine within the casing.

The work plies 35 may be fed from any suitable source of supply into the casing through a slot 102 at the rear, said slot being closed by a cushion 103.

Variations may be resorted to within the scope of the invention, and portions of the improvements may be used without others.

Having thus described my invention, I 105 claim:

1. A sound-deadening casing for a continuous billing typewriting machine comprising a frame with a keyboard extension and a carriage with a swingable platen-displacing frame, said casing comprising a body-part through the front of which said extension projects, and a cover comprising a rearward portion and a forward portion 110 swingable, forward edge first, to a position to rest on said extension and permit forward swinging of the platen-displacing frame, and having a door to permit access to the typewriting machine without shifting said forward portion to its normal position. 115

2. A sound-deadening casing for a continuous billing typewriting machine comprising a frame with a keyboard extension and a carriage with a swingable platen-displacing frame and an upwardly-extending gage fixed to said frame, said casing comprising a body-part through the front of which said extension projects, and a cover 125 comprising a rearward portion and a forward portion forming with the forward 130

- edge of the rearward portion a gage-accommodating slot, said forward portion being swingable, forward edge first, to a position to rest on said extension to permit a forward swinging of the platen-displacing frame, and having a door.
3. A sound-deadening casing for a continuous billing typewriting machine comprising a carriage having a swingable platen-frame and a forwardly-projecting operating handle, said casing comprising a body-part and a cover-part comprising a forward portion and a rearward portion, said forward portion forming with the front wall of the body-part a slot through which said handle projects, and being swingable forwardly to permit swinging of said platen-frame forwardly.
4. A sound-deadening casing for a continuous billing typewriting machine comprising a carriage having a swingable platen-frame and a forwardly-projecting operating handle, said casing comprising a body-part and a cover-part forming a slot with the front wall of the body-part to accommodate said handle and comprising a pivoted frame swingable forwardly to permit swinging of said platen-frame forwardly.
5. A sound-deadening casing for a continuous billing typewriting machine comprising a carriage having a swingable platen-frame and a forwardly-projecting operating handle, said casing comprising a body-part and a cover-part forming a handle-accommodating slot with the front wall of the body-part and having depending ears, at opposite sides of said body-part, to form a cover swing-frame pivoted on said body-part and swingable forwardly to permit swinging of said platen-frame forwardly.
6. A sound-deadening casing for a continuous billing typewriting machine, said machine comprising a carriage having a swingable platen-frame, said casing comprising a body-part and a cover-part, said cover-part comprising a forward portion and a rearward portion, said forward portion being swingable forwardly to permit swinging of said platen-frame forwardly, and a door in said forward portion to permit access to the typewriter mechanism without swinging said forward portion forwardly.
7. A sound-deadening casing for a continuous billing typewriting machine, said machine comprising a carriage having a swingable platen-frame, said casing comprising a body-part and a cover-part, said cover-part comprising a forward portion and a rearward portion, said forward portion being swingable forwardly to permit swinging of said platen-frame forwardly, a door in said forward portion to permit access to the typewriter mechanism without swinging said forward portion forwardly, and a window in said door to permit the machine in the interior of the casing to be viewed when said forward portion is in its rearward position.
8. A sound-deadening casing for a continuous billing typewriting machine, said machine comprising a carriage having a swingable platen-frame and an upwardly-extending gage fixed to said frame, said casing comprising a body-part and a cover-part, said cover-part comprising a forward portion and a rearward portion, said portions forming a slot through which said gage extends, said forward portion being swingable forwardly to permit said platen-frame and gage to be swung forwardly.
9. A sound-deadening casing for a continuous billing typewriting machine, said machine comprising a carriage having a swingable platen-frame, an upwardly-extending gage fixed to said frame, said casing comprising a body-part and a cover-part, said cover-part comprising a forward portion and a rearward portion, said portions forming a slot through which said gage extends, and sound-deadening means carried by said portions adjacent the slot for closing said slot, said forward portion being swingable forwardly to permit said platen-frame and gage to be swung forwardly.
10. A sound-deadening casing for a continuous billing typewriting machine, said machine comprising a carriage having a swingable platen-frame, an upwardly-extending gage fixed to said frame, said casing comprising a body-part and a cover-part, said cover-part comprising a forward portion and a rearward portion, said portions forming a slot through which said gage extends, and sound-deadening means carried by said rearward portion adjacent said slot for closing the slot, said forward portion being swingable forwardly to permit said platen-frame and gage to be swung forwardly.
11. Sound-deadening means for a continuous billing typewriting machine comprising a letter-feeding carriage, a rearward extension on said carriage, and a carbon-carriage forwardly and rearwardly reciprocable on said extension, said sound-deadening means comprising a casing having a body-part and a cover-part, and means mounted on said cover-part for operating said carbon-carriage from outside of the casing without interfering with the letter-feeding movement of the carbon-carriage.
12. A sound-deadening casing for a continuous billing typewriting machine comprising a letter-feeding carriage, a rearward extension on said carriage, and a carbon-carriage forwardly and rearwardly reciprocable on said extension, and means mounted

for forward and rearward reciprocation on said casing to operate said carbon-carriage from outside of the casing, the connection between the operating means on the casing 5 and the carbon-carriage being such as to permit a letter-feeding movement of the carbon-carriage.

13. A sound-deadening casing for a continuous billing typewriting machine comprising a carriage, a rearward extension on said carriage, and a carbon-carriage forwardly and rearwardly reciprocable on said extension, a handle mounted for forward and rearward movement on the outside of 10 said casing, and a connection between said handle and said carbon-carriage for moving said carbon-carriage while permitting letter-space movement of the carriage, said connection comprising a member extending 15 through a forwardly and rearwardly extending slot in the casing.

14. A sound-deadening casing for a continuous billing typewriting machine comprising a carriage, a rearward extension on 20 said carriage, and a carbon-carriage mounted for forward and rearward movement on said extension, carbon-carriage-operating means, including a handle, mounted on said casing, and a connection between said operating 25 means and said carbon-carriage for effecting forward or rearward movement of the carbon-carriage when the handle is operated, said connection permitting letter-space movement of said carbon-carriage independent 30 of said operating means.

15. A sound-deadening casing for a continuous billing typewriting machine comprising a letter-feeding carriage, a rearward extension on said carriage, and a carbon-carriage 35 mounted for forward and rearward movement on said extension, operating means mounted for forward and rearward movement on said casing, and a connection between said operating means and said carbon-carriage to cause said carbon-carriage and operating means to move together, said connection comprising a projection carried by 40 said operating means and extending through a forwardly and rearwardly extending slot 45 in said casing, and a laterally-extending bar carried by said carbon-carriage, said projection having a forked end engaging said bar and permitting said bar to slide laterally 50 therein during letter-spacing movement of said carbon-carriage.

16. A sound-deadening casing for a continuous billing typewriting machine comprising a letter-feeding carriage, a rearward extension on said carriage, and a carbon-carriage 55 mounted for forward and rearward movement on said extension, a platform mounted at its edges on the top of said casing for forward and rearward movement, a handle fastened on said platform, and a connection between said handle and

said carbon-carriage to cause them to move forwardly and rearwardly together, said connection comprising a projection carried by said platform and extending through said casing, and a laterally-extending bar 70 carried by said carbon-carriage, said projection having a forked end engaging said bar and permitting said bar to slide laterally therein during letter-spacing movement of said carriage. 75

17. A sound-deadening casing for a continuous billing typewriting machine comprising a letter-feeding carriage, a rearward extension on said carriage, and a carbon-carriage mounted for forward and rearward 80 movement on said extension, a platform mounted at its edges on the top of said casing for forward and rearward movement, a handle for operating said platform, and a connection between the handle and said carbon-carriage to cause said carbon-carriage and platform to move forwardly and rearwardly together, and comprising a projection carried by said platform and extending through said casing, and a laterally-extending 85 bar carried by said carbon-carriage, said projection engaging said bar to move the bar forwardly and rearwardly and permitting said bar to slide laterally thereof during letter-spacing movement of said carriage. 90

18. A sound-deadening casing for a continuous billing typewriting machine, said machine comprising a carriage, a rearward extension on said carriage, and a carbon-carriage mounted for forward and rearward 95 movement on said extension, said casing comprising a body-part and a cover-part, operating means mounted for forward and rearward movement on said cover-part, and a connection between said operating means 100 and said carbon-carriage whereby forward or rearward movement of the carbon-carriage or the operating means will cause said carbon-carriage and operating means to move together, said connection permitting 105 letter-space movement of said carbon-carriage independent of said operating means, said cover-part being hinged to said body-part and swingable upwardly to expose said carriage extension, said connection being 110 broken when said cover-part is swung upwardly. 115

19. A sound-deadening casing for a continuous billing typewriting machine, said machine comprising a carriage, a rearward extension on said carriage, and a carbon-carriage mounted for forward and rearward movement on said extension, said casing comprising a body-part and a cover-part, operating means mounted for forward and rearward movement on said cover-part, and a connection between said operating means 120 and said carbon-carriage whereby forward or rearward movement of the carbon-carriage or the operating means will cause said 125 130

- carbon-carriage and operating means to move together, said connection comprising a projection carried by said operating means and extending into said casing, and a laterally-positioned bar carried by said carbon-carriage and engageable by said projection, said connection permitting letter-space movement of said carbon-carriage independent of said operating means, said cover-part 5 being hinged to said body-part and swingable upwardly to expose said carriage-extension, said projection disengaging said bar when said cover-part is swung upwardly.
20. A sound-deadening casing for a continuous billing typewriting machine comprising a carriage having a platen-displacing frame, a rearward extension on said carriage, and a carbon-carriage mounted for movement on said rearward extension, said 10 casing comprising a body-part, a top, said top comprising a cover for the front of the machine, the forward edge of the cover overlying the front wall of the body-part, and a rearward portion for covering said rearward extension, and a support for each side of the cover, outside of the body-part and pivoted to the adjacent wall thereof so that the cover may be swung, with its forward edge foremost, to a position in front of the body-part.
21. A sound-deadening casing for a continuous billing typewriting machine comprising a carriage having a swingable platen-displacing frame, a rearward extension on said carriage, and a carbon-carriage mounted for movement on said rearward extension, said casing comprising a body-part and a top comprising a cover swing-frame for covering the top of the machine 15 at the front, and a rearward portion for covering said rearward extension, said cover swing-frame being pivoted on said body-part and swingable forwardly, with its forward edge in advance, to uncover the top of the machine at the front, and said rearward portion being hinged at the rear to said body-part and swingable upwardly to uncover said rearward extension.
22. A sound-deadening casing for a typewriting machine having a frame with a keyboard extension, said casing comprising a body-part through the front of which the extension projects and a cover shiftable to rest with its forward edge on said extension.
23. A sound-deadening casing for a continuous billing typewriting machine comprising a carriage having a swingable platen-displacing frame and a gage fixed to said frame, an operating handle extending 20 forwardly from said carriage, a rearward extension on said carriage, and a reciprocable carbon-carriage on said extension, said casing comprising a body-part and a top comprising a forward cover forming with the body-part a slot to receive said handle and being swingable forwardly, with its forward edge in advance, to uncover the top of said machine at the front, and a rearward cover swingable upwardly and rearwardly to uncover said extension, the rearward edge 25 of said forward cover and the forward edge of said rearward cover forming a slot through which said gage extends.
24. A sound-deadening casing for a continuous billing typewriting machine, said machine comprising a carriage for a swingable platen-frame and a gage fixed to said frame, various operating levers extending forwardly from said carriage, a rearward extension on said carriage, and a carbon-carriage mounted for movement on said extension, said casing comprising a body-part and a cover-part, said cover-part comprising a forward portion and a rearward portion, said forward portion being swingable forwardly to uncover said machine at the front, said rearward portion being swingable rearwardly to uncover said extension, the forward edge of said forward portion forming with said body-part a slot at the front through which said carriage-operating levers extend, the rearward edge of said forward portion and the forward edge of said rearward portion forming a slot through which said gage extends, and means mounted on said rearward portion and connected to said carbon-carriage whereby said carbon-carriage may be operated from outside of the casing.
25. A sound-deadening casing for a typewriting machine having a frame with a keyboard extension, said casing comprising a body-part and a top composed of two elements, a forward element mounted on the body-part for movement, forward edge foremost, to a position to rest on said extension, and a rearward element mounted on said body-part for movement to a position to uncover the rearward portion of the body-part.
26. A sound-deadening casing for a continuous billing typewriting machine, said machine comprising a letter-feeding carriage, a rearward extension on said carriage, and a carbon-carriage reciprocable on said extension, and means for operating the carbon-carriage from the exterior of said casing.
27. The combination with a typewriting machine having a main frame, a carriage having a rearward extension and mounted to travel laterally on said main frame, and a carbon-carriage mounted to travel forwardly and rearwardly on said extension, of a support fixed against lateral movement relatively to said main frame, an actuating device reciprocable forwardly and rearwardly on said support, and a connection between said actuating device and said carbon-carriage, effective to move the carbon-carriage, with the actuating device, for

wardly and rearwardly and permitting the carbon-carriage to move laterally relatively to the actuating device.

28. The combination with a typewriting machine having a main frame, a carriage on said main frame, a rearward extension on said carriage, said carriage and rearward extension mounted to travel laterally on said main frame, and a carbon-carriage 10 mounted to travel forwardly and rearwardly on said extension, of a support fixed relatively to said main frame, an actuating device on said support, a cross-bar on said carbon-carriage, and a slotted arm on said 15 actuating device to engage said cross-bar, so that the carbon-carriage may be moved forwardly and rearwardly by the actuating device and also allow the carbon-carriage to move laterally with respect to the actuating 20 device.

29. A sound-deadening casing for a typewriting machine having a frame with a keyboard-extension, comprising a body-part through the front of which the extension 25 projects, a cover for the front part of the body-part shiftable to rest on said extension, a cover for the remainder of the body-part, and a door in one of said covers.

30. The combination with a continuous 30 billing typewriting machine having a main frame supporting a carriage, a platen on said carriage around which a web comprising a plurality of work-plies with interleaved carbon-sheets may be fed, and an extension behind said frame over which the web may be conducted to the platen, of a sound-deadening casing to enclose said machine, said casing having a top rear cover pivoted at its rear end to said casing, which 40 cover may be swung up to give access to the devices on the rearward extension, a top front cover extending over the carriage of the machine, the front cover being pivotally supported on the sides of said casing and 45 considerably below the cover proper, so that it may be swung forwardly and downwardly in front of the machine to give access to the carriage and enable the straightening out of the web for a carbon-shift operation.

50. 31. A sound-proof casing for a typewriting machine having a carriage and devices on the carriage extending therefrom, said casing comprising a cover extending in the direction of travel of the carriage to keep 55 the casing closed, said cover having two edges, the cover forming along said edges with the casing two slots through which said devices on the carriage may project to the exterior of the casing and move back and forth in said slots, said cover being so supported 60 on the casing that it may be swung to open the casing without interference with the devices extending out of the cover, and yielding devices at both edges of the cover to keep the slots sealed and enable the devices on the carriage to move back and forth freely in said slots.

32. The combination with a typewriting 65 machine having a carriage and a device

mounted on said carriage and extending upwardly therefrom, of a sound-deadening casing for said machine, said casing comprising a body-part and a cover, said cover being pivoted on said body-part considerably below the cover proper near the front of said casing, so that the cover may be swung forwardly and downwardly towards the keyboard to give access to the platen and below the reach of the typist to the platen. 70

33. The combination of a typewriting machine having a frame with a keyboard-extension and a carriage having a forwardly-extending finger-piece, a sound-deadening casing for said machine, said casing comprising a body-part and a cover co-operating with the top of the casing front to form a slot to accommodate the travel of the finger-piece, the cover being so pivoted as, when swung forwardly and downwardly, to 80 open the casing, said finger-piece being curved downwardly at the front of the upper edge of the casing front to avoid interference with the forward swinging of the cover. 85

34. A sound-deadening casing for a typewriting machine having a frame with a keyboard-extension and a carriage, comprising a body-portion having protruding pockets at the top to accommodate the travel of the carriage, brackets extending downwardly from the outer ends of said pockets, and a cover having downward extensions at its sides pivoted on said brackets for swinging said cover to open position. 90

35. The combination with a continuous billing typewriting machine having a reciprocable carbon-carrier, of a sound-deadening casing having a cover, an operating handle supported to travel on the outside of said cover, and a connection extending through a slot in said cover from said handle to said carbon-carrier, said connection to travel back and forth in said slot. 105

36. A sound-proof casing for a typewriting machine, having a carriage and devices on the carriage extending therefrom, said casing comprising a cover extending in the direction of travel of the carriage to keep the casing closed, said cover having two edges, the cover forming along said edges with the casing two slots through which the devices on the carriage project to the exterior of the casing and move back and forth in said slots, said cover being so supported 110 on the casing that it may be swung to open the casing without interference with the devices extending out of the cover, and yielding devices at both edges of the cover to keep the slots sealed and enable the devices on the carriage to move back and forth 115 freely in said slots.

37. The combination with a continuous billing typewriting machine having a displaceable platen to facilitate straightening 120

out of the web conducted around said platen, so as to enable the displacement of carbon-sheets interleaved between the work-plies of the web, of a sound-deadening casing for said machine, said casing having a cover thereon, said cover having two downwardly-extending arms by which the cover is pivotally supported on the sides of said casing, so that it may be swung forwardly and downwardly to enable the swinging up of the platen and the straightening out of the web.

38. The combination with a continuous billing typewriting machine having a main frame supporting a carriage, a platen on said carriage around which a web comprising a plurality of work-plies with interleaved carbon-sheets may be fed, an extension behind said frame over which the web may be conducted to the platen, and devices on said extension, of a sound-deadening casing to enclose said machine, said casing having a top rear cover pivoted at its rear end to said casing, which cover may be swung up to give access to the devices on the rearward extension, a front top cover extending over the carriage of the machine, said front cover being pivotally supported on the sides of said casing and considerably below the cover proper, so that it may be swung forwardly and downwardly in front of the machine to give access to the carriage and enable the straightening out of the web for a carbon-shifting operation, and a door pivoted on the forward cover, which door may be open rearwardly to give access to the printing line of the platen for the purpose of making erasures.

39. The combination with a continuous billing typewriting machine comprising a carriage including a platen around which a continuous web comprising work-plies with interleaved carbon-sheets may be fed, and a carbon-carrier shiftable away from the platen to shift the carbon-sheets relatively to the work-plies, of a sound-proof casing to enclose said machine, a finger-piece mounted on the outside of said casing, and a connection from said finger-piece to said carbon-carrier to actuate the latter at right angles to the travel of said carriage to shift said carbons while the casing remains closed.

40. The combination with a continuous billing typewriting machine comprising a carriage including a platen around which a continuous web comprising work-plies with interleaved carbon-sheets may be fed, and a carbon-carrier shiftable away from the platen to shift the carbon-sheets relatively to the work-plies, of a sound-proof casing to enclose said machine, a handle supported on the outside of said casing for movement at right angles to the direction of travel of the carriage, and means com-

prising a connection between the two associated devices, namely, the handle and the carbon-carrier, said means comprising a bar extending lengthwise of the carbon-carrier and supported on one of said associated devices and a bifurcated arm on the other one of said associated devices to embrace said bar, said connecting means permitting of a movement of the carbon-carrier from side to side of the machine independently of the handle and enabling the carbon-carrier to be actuated to shift the carbons while the casing remains closed and in any position of the carriage.

41. The combination with a continuous billing typewriting machine comprising a carriage including a platen around which a continuous web comprising work-plies with interleaved carbon-sheets may be fed, and a carbon-carrier supported at the rear of said carriage to travel therewith, said carbon-carrier being shiftable rearwardly from the platen to shift the carbon-sheets relatively to the work-plies, of a sound-deadening casing comprising a cover extending over the carbon-carrier, which cover may be swung up to open the casing to give access to the carbon-carrier for changing the carbons from the carbon-carrier, an operating handle mounted to travel back and forth on said cover at right angles to the travel of said carriage, said cover having a slot extending in the direction in which the handle moves, an arm extending through said slot into the casing, and a bar on said carbon-carrier and extending at right angles to the direction in which the handle moves, so as to maintain a connection between the handle and said carbon-carrier in any lateral position of the carbon-carrier, so that the carbon-carrier may be actuated to shift the carbon-sheets while the casing remains closed, the connection between said arm and said bar on the carbon-carrier being such as to permit the arm to leave the bar to swing upwardly with the handle to enable the cover to be raised.

42. The combination with a typewriting machine having a carriage and a device mounted on said carriage and extending upwardly therefrom, of a sound-deadening casing for said machine, said casing comprising a body-part and a cover, said cover being pivoted on said body-part in such a manner as to be swung forward away from the device on the carriage to open the cover to permit said device to be manipulated and to give access to the platen.

43. The combination with a typewriting machine having a carriage and a device mounted on said carriage and extending upwardly therefrom, of a sound-deadening casing for said machine, said casing comprising a body-part and a cover, said cover

- being pivoted on said body-part considerably below the cover proper near the front of said casing, so that the cover may be swung forwardly and downwardly towards the keyboard to give access to the platen and below the reach of the typist to the platen, and a door on said cover which may be actuated independently of the cover to open the casing to give access to the platen for the purpose of making erasures on a work-sheet around the platen without swinging the whole cover. 5
44. The combination with a continuous billing typewriting machine comprising a carriage having a gage-bar extending upwardly from the carriage towards the rear of the machine, and a line-space handle extending forward from said carriage, of a sound-deadening casing for said machine, 10 said casing comprising a body-part and a cover pivoted on said body-part, said cover forming along its opposite edges two slots with the body-part of the casing, namely, a forward slot and a rearward slot, the 15 gage-bar extending through the rearward slot and the line-space handle extending through the forward slot, the cover being arranged to swing in a direction not to be interferred with by the line-space handle and the gage-bar to open the casing to give 20 access to the interior. 30
45. A combined typewriting machine and sound-deadening casing therefor, the casing comprising a body-part and a hinged cover member having a window for viewing the work, the machine having a keyboard projecting forwardly through the casing, and said cover hinged upon said casing to swing forwardly and downwardly to a position in front of the keyboard. 35 40
46. A sound-deadening casing for a type-writing machine, comprising a body-part having an opening through which the keyboard of the machine extends, and a two-part cover seated on the top of the body when closed, the front part mounted to swing outwardly beyond the keyboard when open, thereby giving access to the keyboard. 45

JOHN WALDHEIM.
